UNITED STATES PATENT OFFICE.

CHARLES J. NASH, OF CHICAGO, ILLINOIS, ASSIGNOR TO UNIVERSAL DRAFT GEAR ATTACHMENT CO., A CORPORATION OF ILLINOIS.

DRAFT-GEAR YOKE.

1,074,733.

Specification of Letters Patent.

Patented Oct. 7, 1913.

Application filed July 25, 1912. Serial No. 711,482.

To all whom it may concern:

Be it known that I, CHARLES J. NASH, a citizen of the United States, and resident of Chicago, county of Cook, and State of Illinois, have invented certain new and useful Improvements in Draft-Gear Yokes, of which the following is a specification, and which are illustrated in the accompanying drawings, forming a part thereof.

10 The invention relates to cast metal yokes for draft gears for railway cars; its object being to secure great strength with a small weight of metal.

15 The embodiment of the invention is illustrated in the accompanying drawings, in which—

Figure 1 is a side elevation of the yoke; Fig. 2 is a longitudinal plan section thereof on the line 2—2 of Fig. 1; Fig. 3 is a detail 20 in perspective, partly in section; and Fig. 4 is a cross-section on the line 4—4 of Fig. 1.

The yoke is a casting preferably of steel, its body being in the conventional U-shaped form approved by the Master Car Builders 25 Association and, when desired, having, as shown, bridges intermediate of its ends for engagement with forward and intermediate followers. The top and bottom longitudinal members of the yoke are represented, respectively, at 10, 11, and its rearward bowed end at 12, these members being preferably of uniform thickness and of such width as 30 may be required to afford adequate strength. The bowed end of the yoke is provided with cheek-plates 13, 14, which extend forwardly 35 from the bow 12 and are integral therewith and preferably of substantially the same thickness.

The forward margins of the plates 13, 14, 40 are united intermediate of their ends by a bridge plate 15, which is cast integral with and is preferably of substantially the same thickness as said plates. The forward face of the bridge plate 15 is perpendicular to the 45 axis of the yoke and forms a seat for a rearward follower.

When the yoke is adapted for use with a so-called tandem gear, it is provided with a pair of bridge plates 16, 17, uniting the side 50 members 10 and 11 and being preferably of equal thickness therewith, and being located, respectively, at the margins thereof. The plates 16, 17, are united at their margins, and intermediate the ends thereof, with 55 cross webs 18, 19, which are cast as integral

parts of the yoke, and the thickness of which is preferably substantially the same as that of the parts already described. The width of the bridge plates 16, 17, is such that the webs 18, 19, are spaced apart, and 60 the remoter faces of these two webs are perpendicular to the axis of the yoke and form seats for intermediate followers.

Under some circumstances it is found advisable to extend the yoke forwardly beyond 65 the shock-absorbing elements of the gear a greater distance than is necessary to accommodate the inner end or butt of a coupler bar, and the yoke as illustrated in the drawings is so made. In such an elongated yoke 70 it is necessary to provide a filler for transmitting buffing stresses from the butt of the coupler to the forward follower, and for this purpose an additional pair of bridging plates 20, 21, similar to the plates 16, 17, is 75 provided; these plates uniting the margins of and being cast integral with the side members 10, 11, of the yoke, their width being determined by the extent to which it is desirable to space the butt of the coupler bar 80 from the forward follower.

The margins of the plates 20, 21, intermediate of their ends are united by integral webs 22, 23, the remoter faces of which 85 form bearings, respectively, for the butt of the coupler bar and the forward follower. The plates 20, 21, and the webs 22, 23, are preferably all of substantially the same thickness as the side members 10, 11, of the 90 yoke.

Preferably the union of the plates 20, 21, with the side members 10, 11, does not extend for the entire width of the plates, their forward portions being of less length than the distance between the yoke members, 95 leaving interspaces, as shown at 24, 25. The forward ends of the members 10, 11, are flanged inwardly, as shown at 26, 27, to engage shoulders on the coupler bar, and rivet or bolt-holes, as 28, 29, are provided for the 100 accommodation of securing means for attaching a coupler bar to the yoke. In practice it is frequently found that the butts of coupler bars do not fit exactly between the side members of a yoke, it being customary to put into service such parts as they come from the foundry and without machining. The separation of the forward portions of the bridge plates 20, 21, from the yoke members 10, 11, permits the flexure of the latter 110

either outwardly or inwardly to adapt them to receive coupler butts which exceed the intended dimension, or to be drawn down upon butts which fall below the intended 5 measurement.

The yoke constructed as described provides the essential strength in its various parts without the massing of metal, and thereby not only avoids unnecessary weight 10 but also eliminates the risk of fractures due to shrinkage in cooling the casting.

I claim as my invention—

1. In a draft gear yoke, in combination, a 15 pair of longitudinal members, a cross member uniting the rear ends thereof, cheek plates extending forwardly from the side edges of the cross member, and a bridge plate uniting the cheek plates at their forward edges and being spaced apart from the 20 longitudinal members.

2. In a draft gear yoke, in combination, a 25 pair of longitudinal members, a cross member uniting the rear ends thereof, bridge plates uniting the margins of the longitudinal members intermediate of their ends, and webs uniting the bridge plates at both of their margins and being spaced apart from the longitudinal members.

3. In a draft gear yoke, in combination, a 30 pair of longitudinal members, a cross member uniting the same at their rear ends, bridge plates uniting the margins of the longitudinal members and located adjacent the forward ends thereof, a web uniting the 35 bridge plates at their forward margins and forming a seat for a coupler butt and being

spaced apart from the longitudinal members.

4. In a draft gear yoke, in combination, a 40 pair of longitudinal members, a cross member uniting the same at their rear ends, bridge plates uniting the margins of the longitudinal members and located adjacent the forward ends thereof, the bridge plates extending forwardly beyond the point of their 45 attachment to the longitudinal members, a web uniting the bridge plates at their forward margins and forming a seat for a coupler butt.

5. In a draft gear yoke, in combination, a 50 pair of longitudinal members, a cross member uniting the same at their rearward ends, a pair of cheek-plates extending forwardly from the cross member, a bridge plate uniting the cheek-plates at their forward margins, a pair of bridge plates uniting the longitudinal members at their margins intermediate of their ends, webs uniting both 55 margins of the bridge plates, a pair of bridge plates uniting the longitudinal members at their margins and adjacent their forward ends, and webs uniting both margins of the last-named bridge plates; all of the 60 named elements being cast integrally and being of substantially the same thickness the 65 several named webs being spaced apart from the longitudinal members.

CHARLES J. NASH.
